UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW-REGULATOR WHEEL SUPPORT.

Application filed August 23, 1922. Serial No. 583,723.

To all whom it may concern:

Be it known that I, ERNEST E. HEINTZ, a citizen of the United States, residing at Detroit, in the county of Wayne and State 5 of Michigan, have invented certain new and useful Improvements in Window-Regulator Wheel Supports, of which the following is a specification.

This invention relates to window regulators and especially to the mounting for the lower rotatable member which is either a pulley wheel or a sprocket wheel. In a prior patent to Allmand and Lawrence, #1,317,150, there is described and claimed 15 an improvement of this nature which has a very limited turning movement about a vertical axis. It is the purpose of a mounting of this kind to permit the lower pulley or sprocket wheel to twist slightly on a vertical 20 axis so as to prevent the chain or cable from running off the sprocket when the upper pulley wheel or sprocket is so placed as to tend to pull the cable or chain off the lower member. 25 It is the object of the present invention to provide a carrier for the lower rotatable member which is both slidable vertically and has a considerable turning range on the vertical axis. Furthermore, the construction can be made in the form of a stamping and is relatively much cheaper than that described in the Allmand and Lawrence Patent No. 1,317,150.

In the drawings:

35 Fig. 1 is an inside elevation of a door equipped with a window regulator containing the improved mounting.

Fig. 2 is a vertical section on the line 2—2 of Fig. 1.

40 Fig. 3 is a view taken on the line 3—3 of Fig. 2.

Fig. 4 is a perspective of a yoke member.

The various parts of the regulator will be plain enough from the elevational view. It 45 matters not so far as this invention is concerned what the form of the flexible draft member is, whether it is a cable or a chain. It makes no difference what form the upper rotatable member takes; in the drawings it 50 is shown as an elongated drum *a*, on which a cable *c* winds. The lower rotatable member in the drawings takes the form of a pulley wheel designated *d*, although obviously it might be a sprocket wheel as 55 shown in the prior Allmand Patent No.

1,317,150. Riveted to the vertical strap iron *e*, are a pair of ears *f*, which are perforated to permit the rod *g* to pass slidably there-through. This rod is secured through the ends of the yoke or carrier *h*, which is provided with a pin *i* on which rotates the pulley wheel *d*. The coiled spring *j* at its top end engages against the ear *f* and at its bottom end pushes against the lower end of the yoke and consequently always tensions 60 the draft member and automatically takes up any slack.

The yoke member faces toward the strap iron frame *x* and the ears *f* and this permits the carrier on the rotatable pulley to twist 70 on a vertical axis through a considerable number of degrees. Not only is the number of degrees of twisting increased over that shown in the prior patent, but the arc on which the pulley wheel moves has a very 75 much larger radius and consequently the pulley wheel can move automatically laterally to either side a larger distance than is the case with the prior construction. This therefore, permits the device to automatically adjust itself to any strains imposed by 80 different locations of the upper parts of the regulator. The carrier itself being a simple strap iron yoke member, it is much cheaper to manufacture than the casting shown in 85 the prior patent.

What I claim is:

1. In a window regulator, the combination of a frame, a carrier member provided with a vertical projecting rod, means connected 90 with said frame for slidably and rotatably supporting said rod, one or more of the end portions of the carrier engaging rod, and a rotating member rotatably supported by an intermediate portion of the carrier at a 95 point somewhat radially removed from the axis of the rod, whereby the said carrier member and rotating member are both slidable and rotatable on a vertical axis with respect to said frame on an arc of relatively 100 large radius.

2. In a window regulator, the combination of a frame, an ear projecting from the frame and provided with a perforation, a yoke in the form of a stamping provided with a rod 105 slidably and rotatable in said perforation of the ear, and a rotatable member rotatably supported by said yoke.

3. In a window regulator, a combination of the frame, a perforated ear projecting 110

from the frame, a yoke provided with arms, a rod secured through the arms of the yoke and slidably and rotatably supported by the perforated ear, and a rotatable member supported by the yoke.

4. In a window regulator, the combination of a frame provided with a perforated ear, a yoke facing toward the frame and ear, a rod supported by the ends of the yoke and 10 passing through the perforated ear, a spring coiled about the rod and abutting at one end against the perforated ear and at the other end against the inside of one of the yoke arms, and a rotatable member supported by the yoke.

5. In a window regulator, the combination of a frame provided with a pair of perforated ears, a yoke having the arms of the yoke one on the outside of the ears and the other between the ears and facing towards 20 the ears and the frame, a rotatable member supported on the yoke, a rod secured to the ends of the yoke, and slidably and rotatably supported in the two perforated ears, and a coil spring about the rod having one end 25 abutting against one ear and the other end abutting against the arm of the yoke between the two ears.

In testimony whereof I affix my signature.
ERNEST E. HEINTZ.
